(57) **CLAIM**

The ornamental design for a stand for kitchen utensils, as shown and described.

DESCRIPTION

FIG. 1 is a front view of a stand for kitchen utensils, shown in environmental use, showing my new design;

FIG. 2 is a rear view thereof, shown in environmental use;

FIG. 3 is a right side view thereof, shown in environmental use;

FIG. 4 is a left side view thereof, shown in environmental use;

FIG. 5 is a top plan view thereof, shown in environmental use;

FIG. 6 is a bottom plan view thereof, shown in environmental use;

FIG. 7 is a cross-sectional view thereof, taken along line 7-7 of FIG. 5, shown in environmental use;

FIG. 8 is a front view thereof;

FIG. 9 is a rear view thereof;

FIG. 10 is a right side view thereof;

FIG. 11 is a left side view thereof;

FIG. 12 is a top plan view thereof; and,

FIG. 13 is a bottom plan view thereof.

The broken lines in FIGS. 1-7 illustrate environmental subject matter that form no part of the claimed design.
